UNITED STATES PATENT OFFICE.

AUGUST C. DITTRICH, OF CHICAGO, ILLINOIS.

TIME CONTROL FOR SOUND-REPRODUCING MECHANISM.

1,337,760.

Specification of Letters Patent. Patented Apr. 20, 1920.

Application filed May 22, 1919. Serial No. 298,836.

To all whom it may concern:

Be it known that I, AUGUST C. DITTRICH, a citizen of the United States, residing at Chicago, in the county of Cook and State 5 of Illinois, have invented certain new and useful Improvements in Time Control for Sound-Reproducing Mechanism, of which the following is the specification.

This invention relates to time control 10 mechanism and is especially applicable for starting a sound reproducing mechanism at a predetermined hour.

My present invention embodies improvements over the disclosure of my co-pending 15 applications, Serial Numbers 265,684, filed December 7, 1918, and 281,158, filed March 7, 1919.

Among the objects of this invention is to provide an improved construction of apparatus 20 for setting into operation, at a predetermined hour, a sound reproducing mechanism; further, to provide such device that will still possess all of its desirable features as an alarm or ordinary clock when 25 not in use otherwise; further, to provide means for automatically throwing the bell out of ringing position when the brake is moved into operative position; further, to effect the automatic return of the bell to 30 ringing position when the alarm mechanism is being wound; further, to provide means for the prevention of the continued noise and operation of the alarm mechanism after 35 the brake has been released; further, to simplify, render more positive in action, attractive in appearance, economical and efficacious, apparatus of the class described; and such further objects, advantages, and capabilities as will later more fully appear.

40 My invention further resides in the combination, construction and arrangement of parts illustrated in the accompanying drawings, and while I have shown therein a preferred embodiment, I desire the same to be 45 understood as illustrative only and not as limiting my invention.

In the drawings:

Figure 1 is a fragmentary perspective view showing a portion of the sound repro-

ducing apparatus having my invention applied thereto.

Fig. 2 is a vertical sectional view through the casing of my improved apparatus showing the clock in elevation.

Fig. 3 is a vertical transverse section 55 through the casing and showing the clock and certain other parts in elevation.

Fig. 4 is a perspective view of the removable back of the casing and showing the operating mechanism attached thereto; the 60 brake being shown in extended position and the parts in the position assumed by them just prior to the release of the alarm mechanism.

Fig. 5 is a view similar to Fig. 4 but 65 showing the alarm mechanism as having been released and the winding stem having rotated sufficiently to release the brake.

Fig. 6 is a view similar to Fig. 5 with the rotation of the winding stem having been 70 continued to a position to stop the alarm mechanism.

Fig. 7 is a view similar to Fig. 6 but showing the winding stem as having been rotated in the opposite direction by re-wind- 75 ing to a position to return the bell into operative position.

Fig. 8 is a horizontal sectional view taken just above the brake and showing the brake head in engagement with the rotatable table 80 and the sound reproducing mechanism.

Referring to the drawings, it will be seen that my invention contemplates a device for effecting the operation of a sound reproducing mechanism at a pre-determined time, 85 and comprises the casing 1, in which is suitably mounted a clock 2, carrying upon its top an alarm bell 3, and suitably mounted in its lower portion the brake 4 which, as shown in Figs. 1-8, when moved into ex- 90 tended position is adapted to be placed in contact with the edge of the rotatable disk carrying table of a sound reproducing mechanism such as a phonograph, so universally found in the home, by releasing the 95 brake 4 at a predetermined time, the phonograph table will be released for rotation.

The back plate 5 of the casing is remov-

able and has attached thereto the major portion of the mechanism for effecting the various operations, as seen in Figs. 4-7. Secured adjacent the bottom of the back 5 plate 5 by means of screws 6 or the like is the bracket 7 provided with an aperture to slidably receive the stem 8, carrying the brake head 4. The end of the stem 8 is also slidably mounted in the aperture 9 of the 10 front face of the casing, as clearly seen in Figs. 3 and 8. The brake head 4 is slidably mounted in a suitable slot or opening 10 in the back plate 5 and carries in its upper side the projection or shoulder 11, with 15 which is adapted to be engaged when the brake is in extended position by the lip 12 of sliding catch bar 13, which is guided in its sliding movements by the screws 14, fitting in slots 15. Formed in catch bar 13 is 20 a slot 16 adapted to receive the lower end of the lever 17, which is pivotally mounted at 18 and carries at one side of said pivot the cam face 19, and at the opposite side the extended arm 20, carrying the pin 21, with 25 which is engaged one end of the spring 22, while the other end of said spring is secured to pin 23 mounted in the back plate 5. Spring 22 normally tends to move catch bar 13 to the left as viewed in Figs. 4 to 7, where- 30 by when the brake rod 8 is moved into extended position by pressure upon the ex- posed forward end 24, the lip 12 will move in front of projection 11, whereby to hold said brake extended until said bar 13 is 35 forced to the right, as later described.

Mounted in brake rod 8 is a pin 25 adapted to engage with lug 26 of lever arm 27, which is mounted on pin 28, carried by bracket 29, which is in turn secured to 40 back plate 5. The upper end 30 of lever 27 engages lever 31, which is pivoted to the back plate at 32 and engages at its forward end with the slot 33 in the lower end of the vertical sliding bar 34, which at suitably 45 spaced intervals is provided with elongated slots 35, through which extend screws 36 se- cured to the back plate 5, whereby to permit longitudinal movement of said bar.

Rotatably mounted in a suitable aperture 50 in back plate 5 is a bearing plate 37, carry- 55 ing at one side the arm 38 and at its lower portion the projection 39, in which is se- cured the pin 40, forming a connecting means for one end of the spring 41, the 60 opposite end of which is secured to pin 42 mounted in the backing plate. Centrally formed in plate 39 is the aperture 43, which is of square or other non-circular formation, and into which is adapted to be inserted the end 44 of shaft 45, upon which is pivotally mounted the bell 3. It will of course be understood that the end 44 will be of a cross -section similar to that of the opening 43, whereby rotation of the plate 37 will

rotate shaft 45 and swing said bell 33 into 65 or out of operative position, as hereinafter set forth. Arm 38 is adapted to have articu- 70 lation with the upper lateral offset end 46 of bar 34 by means of the recess 47.

As will be noted in Figs. 4-7, the sliding 75 bar 34 is provided at one edge with the notch 48, within which is adapted to seat the end 49 of the horizontally arranged sliding bar 50, which is formed with the depending arm 51 formed on one side with the curved face 52 and at its bottom end with the square 80 face 53. Plate 50 is capable of a limited sliding movement by virtue of slots 54, through which extend screws or other suitable securing means 55. The bar 50 is 85 normally moved to the left as viewed in these figures by means of spring 56, which is secured at one end to pin 57 mounted in back plate 5, and at its other end to pin 58, carried by bar 50.

Pivottally mounted in back plate 5 is the 90 inwardly extending arm 60, carrying pro- jections 61 adapted to be rotated by handle 62, shown in Fig. 1, whereby to lock the alarm mechanism against operation when 95 desired.

The brake rod 8 is normally held in re- 100 tracted position by spring 63, which is se- cured at one end to bracket 7 and at the other end to a pin carried by the brake 95 rod 8.

The winding stem for the alarm mecha- 105 nism is designated in Figs. 4-7 at 64, and has extending therethrough the pin 65, which at one end is formed with the cam 100 wiper 66, and at the other end into the more extended shoulder 67. The bar 34 is formed immediately above the notch 48 with the outwardly extending curved projection 68 for a purpose to be later described.

In the operation of my improved device, the alarm mechanism, which is of the usual 110 type and hence is not shown in detail, will be wound by the rotation of stem 64 in the direction indicated by the arrow in Fig. 7. 115 After the alarm mechanism is wound, the stem 47 and pin 65 will assume the position shown in Fig. 4. In case the clock is to perform its usual functions, the brake stem 8 will be permitted to assume the position shown in Figs. 5, 6, and 7; in other words, it will not be moved or pushed in- 120 wardly from the end 24. This will leave the bell of the alarm mechanism in position to ring in the usual manner, as will be later 125 more fully understood. In case, however, it is desired to use this device for releas- ing a phonograph or the like at a prede- termined hour, the brake stem 8 is pushed in- 125 wardly to bring the brake head 4 into ex- tended position, at which time it will be placed in contact with the edge E of the rotatable table T of the phonograph, as

clearly shown in Fig. 8. This movement of the rod 8 will cause the pin 25 to engage the lug 26, thus swinging lever 27, which in turn will operate lever 31 and elevate 5 the sliding bar 34 in an obvious manner. This upward movement of bar 34 will rotate plate 37 into the position illustrated in Figs. 4, 5, and 6, the result of which is to effect rotation of shaft 45 to swing bell 10 3 into inoperative position to prevent ringing of the same upon release of the alarm mechanism. Also, during this forward movement of brake rod 8, projection 11 will move beyond catch 12 and permit the latter 15 to immediately jump into place on the action of spring 22, whereby to hold brake head 4 in extended position until released. Upward movement of the sliding bar 34 will bring the notch 48 into position to 20 permit the entry into the same of the end 49 of the horizontal sliding bar 50, whereby to lock the bar 34 in elevated position until released, as hereinafter set forth.

The parts are now in the position illustrated in Fig. 4 and, as explained, when the 25 apparatus is being used in connection with a phonograph or the like, the head 4 will frictionally engage the rotatable table E to hold the same against rotation until released. At the predetermined hour (governed by the setting of the alarm dial), the 30 alarm mechanism will be released, causing stem 64 to rotate in the direction of the arrow shown in Fig. 4, which rotation will 35 bring the cam wiper 66 into the position shown in Fig. 5, which will depress cam face 19, moving the lower end of lever 17 to the right, as viewed in this figure, which in turn will cause movement of bar 13 to 40 the right, thus releasing shoulder 11, thereby permitting brake head 4 under action of spring 63 to move inwardly with relation to the casing, whereby to release the rotatable table T and permit operation of the 45 phonograph or the like at said predetermined hour.

It is also important to note that I have provided means for stopping the operation of the alarm mechanism as soon as the brake 50 head 4 is released, whereby to eliminate any possible noise of the alarm mechanism, which would interfere more or less with the enjoyment of the music of the phonograph. This latter result is accomplished by projection 67 of pin 65 assuming by the continued rotation of stem 64 the position 55 shown in Fig. 6, in which it contacts with the end face 53 of projection 51 on bar 50, thus stopping the alarm mechanism 60 from further operation as soon as the brake head has been released. It will be noted that the alarm bell 3 is still in inoperative position, as seen by the position of the square opening 43 in plate 37 of Fig. 6.

As clearly illustrated in Fig. 7, rotation of 65 stem 64 in the opposite direction when re-winding the alarm mechanism will move projection 67 away from depending arm 51 and bring said projection into contact with face 52, as shown in Fig. 7, to cause movement of bar 50 to the right, which, in an obvious manner, will release sliding bar 34 and permit the same on action of spring 41 to move downwardly, thus returning the bell to ringing position. 70 75

It will thus be seen that, in addition to other accomplishments, my improved device will automatically swing the bell into inoperative position upon the setting of the brake head, will return the bell to operative 80 position upon re-winding the alarm mechanism, and will stop operation of the alarm mechanism when the brake head has been released. Curved face 68 holds arm 51 away from contact with projection 67 to permit 85 rotation of stem 64 when the alarm is operating in its ordinary manner.

Having now described my invention, I claim:

1. In apparatus of the class described, 90 alarm mechanism comprising a bell, means for holding a sound reproducing mechanism against operation, means connecting said first mentioned means and said alarm mechanism to release the former by operation of 95 the latter at a predetermined hour, and means for automatically moving the bell into inoperative position upon the movement of said first mentioned means into operative position. 100

2. In apparatus of the class described, alarm mechanism having a pivotally mounted bell, a brake adapted, when extended, to contact with the rotary table of a sound reproducing mechanism to hold the same 105 against rotation, means for releasing the brake upon operation of the alarm mechanism at a predetermined hour, means for moving the bell into inoperative position upon the moving of said brake into operative position, and means for automatically returning the bell to operative position upon the winding of said alarm mechanism. 110

3. In apparatus of the class described, a clock including alarm mechanism having a 115 bell, means controlled by said alarm mechanism for releasing for operation a sound reproducing mechanism at a predetermined hour, and means for automatically moving said bell to inoperative position upon setting 120 said first mentioned means.

4. In apparatus of the class described, a clock including alarm mechanism having a bell, means for holding the rotatable table of a sound reproducing mechanism against 125 rotation, means operated by said alarm mechanism to release said first mentioned means to permit rotation of said table at a

predetermined hour, and means for stopping the operation of the alarm mechanism upon the release of said first mentioned means.

5. In apparatus of the class described, a 5 clock including alarm mechanism having a bell, means for holding against rotation the table of a sound reproducing mechanism, means controlled by said alarm mechanism for releasing said first mentioned means at 10 a predetermined hour, means to automatically move said bell to inoperative position upon the movement of said first mentioned means to operative position, and means to prevent the return of the bell to operative 15 position until the alarm mechanism is rewound.

6. In apparatus of the class described, a 20 clock comprising a frame having a brake slidably mounted therein adapted to contact with the rotatable element of a sound reproducing mechanism, alarm mechanism comprising a winding stem, a projection on said stem, a lever having a cam face whereby said lever will be moved by said 25 projection upon rotation of said stem, and a locking element engaging said lever and said brake to release the latter upon operation of the alarm mechanism at a predetermined hour.

30 7. In apparatus of the class described, a casing having a clock mounted therein, said clock comprising alarm mechanism having a bell pivotally mounted on an axis above said clock, a non-circular extension on said axis, a bearing 35 rotatably mounted in said casing to receive said extension, a brake slidably mounted in said casing adapted when extended to hold a sound reproducing mechanism against rotation, and means connecting said 40 brake and said bearing whereby movement of the brake to operative position will automatically move the bell to inoperative position.

8. In apparatus of the class described, a 45 casing having a clock mounted therein, said clock comprising alarm mechanism having a bell pivotally mounted on an axis above said clock, a non-circular extension on said axis, a bearing rotatably mounted in said 50 casing to receive said extension, a brake slidably mounted in said casing adapted when extended to hold a sound reproducing mechanism against rotation, and means connecting said brake and said bearing whereby 55 movement of the brake to operative position will automatically move the bell to inoperative position, and means operated by the rewinding of the alarm mechanism to return said bell into operative position.

60 9. In apparatus of the class described, a casing having a clock mounted therein, comprising alarm mechanism having a bell, a 120 brake slidably mounted in said casing, means for moving said bell into inoperative

position when said brake is moved to operative position, a winding stem for said alarm mechanism, means for releasing said brake upon rotation of said stem in one direction, and means for moving said bell again into operative position when said stem is rotated 125 in the opposite direction.

10. In apparatus of the class described, a casing having a clock mounted therein, a bell pivotally mounted on said clock, a brake 130 slidably mounted in said casing, and means for automatically moving said bell into inoperative position upon movement of said 135 brake into operative position.

11. In apparatus of the class described, a 140 casing having a clock mounted therein having alarm mechanism including a bell, a brake slidably mounted in said casing, means for moving the bell into inoperative position upon movement of said 145 brake, a winding stem for said alarm mechanism, and means associated with said winding stem, brake, and bell to release said brake upon rotation of the stem in one direction, to stop the 150 actuation of the alarm mechanism after said brake has been released, and to return the bell to operative position upon the rewinding of the alarm mechanism.

12. In apparatus of the class described, a 155 casing having a clock therein, a slidable brake, a releasable catch to hold said brake extended, a lever for actuating said catch, a cam on said lever, alarm mechanism having a winding stem, a second lever operated by forward movement of said brake, a sliding bar operated by said second lever, a 160 bell swingingly mounted on said clock and movable by said bar, a second sliding bar having a catch to hold said first mentioned bar in elevated position, a depending arm on said second sliding bar extending adjacent 165 said stem, whereby rotation of said stem in one direction will actuate said first mentioned lever to release said brake, continued rotation of said stem will stop said alarm mechanism, and rotation in the opposite direction will return said bell to operative 170 position.

13. In apparatus of the class described, a 175 casing, alarm mechanism, a brake slidably mounted therein, means for releasing said brake upon operation of the alarm mechanism, and means for automatically stopping the operation of the alarm mechanism when said brake is released.

14. In apparatus of the class described, a 180 casing, alarm mechanism, a brake operatively connected thereto, means for releasing said brake upon operation of the alarm mechanism, and means for automatically stopping the operation of the alarm mechanism when said brake is released.

15. In automatic release mechanism, alarm mechanism, holding means operatively con-

nected thereto, means for releasing said holding means to release the held mechanism upon operation of the alarm mechanism and means for automatically stopping the 5 operation of the alarm mechanism when said holding means is released.

16. In apparatus of the class described, a clock comprising a frame having a brake 10 slidably mounted therein, adapted to contact with the rotatable element of a sound reproducing mechanism, alarm mechanism

comprising a winding stem, a projection on said stem, a lever having a cam face whereby said lever will be moved by said projection upon rotation of said stem, and means connecting said lever and said brake to release the latter upon operation of the alarm mechanism at a predetermined hour. 15

In witness whereof I hereunto subscribe by name to this specification.

AUGUST C. DITTRICH.
